UNITED STATES PATENT OFFICE.

FREDERICK W. LA CHAPELLE, OF DULUTH, MINNESOTA.

TIRE-REMOVING DEVICE.

1,323,871.

Specification of Letters Patent.

Patented Dec. 2, 1919.

Application filed March 19, 1918, Serial No. 222,921. Renewed June 25, 1919. Serial No. 306,662.

To all whom it may concern:

Be it known that FREDERICK W. LA CHAPELLE, a citizen of the United States, residing at Duluth, in the county of St. Louis 5 and State of Minnesota, has invented certain new and useful Improvements in Tire-Removing Devices; and he does hereby declare the following to be a full, clear, and exact description of the invention, such 10 as will enable others skilled in the art to which it appertains to make and use the same, reference being had to the accompanying drawings, and to the letters and figures of reference marked thereon, which 15 form a part of this specification.

This invention relates to new and useful improvements in devices for facilitating the removing of tires from wheels and consists essentially in the provision of an apparatus 20 for separating and contracting the ends of the rim of a wheel to permit a tire to be applied thereto or removed therefrom.

The invention consists in a simple and efficient device of this nature having various 25 details of construction, combination and arrangement of parts which will be hereinafter fully described, shown in the accompanying drawings and then specifically defined in the appended claims.

30 I illustrate my invention in the accompanying drawings which, with the letters of reference marked thereon, form a part of this specification and in which:

Figure 1 is a top plan view showing the 35 application of my invention to the rim of a wheel.

Fig. 2 is a central vertical sectional view.

Fig. 3 is a cross sectional view, and

40 Fig. 4 is a detail perspective view of the means for separating the ends of the rim laterally to permit the same to be contracted.

Reference now being had to the details of the drawings by letter:

45 A circular disk A having an aperture B through which passes the unthreaded portion of the shaft C has pivoted thereto by their upper ends, a series of bars H provided at their opposite extremities with 50 hooked ends N designed to engage the flange of a split rim. The shaft C has a hand wheel D and turns freely in the aperture of the disk A, but is prevented from longitudinal movement relative thereto by 55 collars shrunk or pinned to the shaft, one above and the other below the disk. A sec-

ond disk has threaded engagement with the lower portion of the shaft and a series of connecting rods O are pivoted respectively to the second disk and to the hooked bars 60 near their curved ends.

Pivotedly mounted upon two of the rods H is a cylindrical rock shaft R having a pin R' projecting therefrom intermediate the bars, said shaft R having a bent portion T forming a handle.

In the application of my invention, the several hooks at the ends of the bars or rods H are caught over the marginal edge of the rim and the rock shaft mounted on 70 two of the bars is so positioned relative to the rim, that the finger R' will be a slight distance from the joint of the rim. By rocking the shaft R in one direction the finger R' bearing against one end of the 75 rim may cause the same to be moved laterally out of alignment with the other end of the rim, after which by turning the hand wheel D the rim may be contracted, one end of the latter overlapping the other 80 which will permit the tire to be removed from the rim.

In replacing the tire, the rim is held in a contracted form, after which the hand wheel is turned in the opposite direction 85 permitting the rim to expand and the rock shaft is thrown back to its normal position, permitting the ends of the rim to come together. By the provision of the device embodying the features of my invention it 90 will be noted that a person may easily and quickly remove and replace the tire without the necessity of the help of a second person, and without the employment of other accessories which are commonly employed for 95 this purpose.

What I claim to be new is—

1. A device for removing tires, consisting of an apertured disk, bars pivoted at one end to the disk and having hooked ends at 100 their other extremities adapted to engage the circumference of a detachable split rim, a shaft having a hand wheel and free to revolve in the aperture of said disk, but held from longitudinal movement relative 105 thereto, a second disk having screw threaded connection with the shaft, rods pivotally connecting the hooked bars and said second disk, and means mounted on the hooked bars for causing the ends of the 110 rim to be moved out of alignment with each other.

2. A device for removing tires, consisting of an apertured disk, bars pivoted at one end to the disk and having hooked ends at their other extremities adapted to engage the circumference of a detachable split rim, a shaft having a hand wheel and free to revolve in the aperture of said disk, but held from longitudinal movement relative thereto, a second disk having screw threaded connection with the shaft, rods pivotally connecting the hooked bars and said second disk, and a rock shaft pivotally mounted

upon said hooked bars, and having a laterally extending finger designed to engage the rim adjacent to one end, and affording means whereby, as the rock shaft is turned in one direction, the ends of the rim may be thrown out of alinement.

In testimony whereof I hereunto affix my signature in presence of two witnesses.

FREDERICK W. LA CHAPELLE.
